UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FUSE BOX.

Application filed October 25, 1920. Serial No. 419,245.

To all whom it may concern:

Be it known that I, GEORGE B. THOMAS, a citizen of the United States of America, residing at Bridgeport, in the county of

5 Fairfield and State of Connecticut, have invented certain new and useful Improvements in Fuse Boxes, of which the following is a specification.

My invention relates to fuse boxes, and 10 particularly to a box for housing a group of small fuses, such as would be installed, for instance, in a wiring system for automobile lights, etc. The object of my invention is to provide a simple and serviceable 15 fitting of economical construction, compact and efficient arrangement of the elements.

In the accompanying drawings

Fig. 1 is a broken perspective of a fuse box in which my invention is embodied in 20 one form;

Fig. 2 is a longitudinal section therethrough;

Fig. 3 is a transverse section; and

Fig. 4 is a perspective of a terminal connector.

The present fuse box comprises a sheet metal casing, the bottom member 5 of which is integral with the bent-up ends 6 and sides 6^a. The sides 6^a are provided with end lugs 7 folded over the ends 6 and secured thereto by rivets 8 passing through registering perforations in the lugs and ends. Each end 6 is apertured at 9 to receive the hinge tongues 10 of a detachable cover 11, having 35 a spring catch 12 at its opposite end, provided with a boss 13 adapted to snap into a hole 14 formed in each end 6 to cooperate therewith. The cover is thus reversible and may be hinged at either end of the box, as 40 most convenient for the position in which the box is installed.

Fitting snugly within the box is a base plate 15 of insulation, upon which are mounted in parallel at spaced intervals 45 pairs of fuse terminal clips 16, the bases of which are engaged by the heads of rivets 17 piercing the insulating plate 15. Associated with each terminal clip is a wire terminal strap 18, also engaged by the rivet 50 head and extending outward toward one or the other of the sides 6^a of the box. Binding screws 19 are tapped into the wire terminal plates. In the construction shown I have shown seven pairs of clips mounted on 55 the base 15, and spaced a suitable distance

apart, the number of clip pairs being of course variable to meet the requirements of the installation.

The side walls 6^a of the box are pierced at 20 in alinement with the axes of the 60 several clip pairs to accomodate the lead wires 21. To insulate the lead wires from the metal of the box, and also to protect them against the cutting of their insulation by the edges of the metal at the apertures 20, I provide a lining sheet 22 of paper, fiber or other suitable insulating material, which extends beneath the plate 15 and is bent upward at its opposite side margins to face the side walls of the box. The 70 lining sheet is apertured in register with the holes 20 in the side walls, the apertures 23 in the sheet being of less diameter than that of the aperture 20, so as to maintain the lead wires out of contact with the edges of 75 the holes 20. To facilitate the introduction of the wires into the holes 20, 23 when the wires are previously provided with soldered terminals 27, such as hereinafter described, the margins of the box sides 6^a are cut by 80 slots 24 leading from the edges to the holes 20. The lining sheet 22 is similarly slotted at 25, these slots being narrower than the slots 24 in the box sides to maintain the wire 85 out of contact with the latter. The lining sheet at the point at which it underlies the base 15 has the further function of insulating the base clip rivets 17 from the metal box bottom, and thus preventing short circuiting the fuses 26 through the box. 90

The connection between the lead wires and the terminal plates 18 is made more secure by utilizing a wire terminal 27 (Fig. 4) having lugs 28 adapted to be clamped down upon the wire and provided with a 95 perforated ear 29, through which the binding screw 19 passes. The bared end 30 of the wire 21 may be either engaged between the head of the binding screw and the ear 29, or it may be passed through a hole 31 100 in the clip 27 and soldered, or it may be engaged between the ear 29 of the clip and the terminal plate 18. When a terminal of this type is applied to the wire end before it is introduced into the box, it is nevertheless 105 readily passed through the holes 20, 23, by turning the terminal on edge so that its ear 29 passes down through the slots 24 and 25 into the holes 20, 23 through which the wire may then be readily pulled. It not in- 110

frequently happens that the ear 29 is of greater diameter than the opening of the holes 20, so that it would not be possible to introduce the terminal into the box were it

5 not for the slots 24 and 25 above mentioned.

The insulating plate 15, lining strip 22, and box bottom 5 are rigidly united by hollow rivets 32, through which the fastening screws 33 pass into the support 34 upon

10 which the fuse box is mounted.

Upon the inner face of the cover 11 of the box I mount a series of pairs of fuse clips 35 adapted to receive a group of reserve fuses, to replace any of the service 15 fuses which may be blown. The clips 35 are mounted on the cover by rivets 36, and are arranged in staggered relation to those on the base 15, so that the fuses which they carry lie between the service fuses when the 20 box is closed, thus insuring a compact unit occupying little room when installed.

The assembly as a whole provides a fuse box of very compact structure, with all current carrying elements fully housed-in and 25 protected against accidental injury and short circuit, while the lead wires are protected against contact with the metal box body even should their insulation be worn through by reason of the vibrations to 30 which the fitting is subjected when mounted on a motor car. Various modifications in details of construction will readily occur to those skilled in the art, without departing from what I claim as my invention.

35 I claim—

1. In a fuse box, a sheet metal body having its opposite sides pierced to afford a series of wire-entry apertures, an insulating base plate fitting within said body and having a series of pairs of fuse-clip terminals which register with the wire-entry apertures in the sides of the box, securing means piercing the base for holding the said clips in position thereon, and a flexible insulating 45 lining supporting said base from the bot-

tom of the box and having up-turned side flanges facing the apertured sides of the box and pierced to admit lead wires to said clips.

2. In a fuse box, a sheet metal body having its opposite sides pierced to afford a series of wire-entry apertures, an insulating base fitting within said body and having a series of pairs of fuse-clip terminals, which register with the wire-entry apertures in 55 the sides of the box, a sheet of flexible insulation lining said box and apertured at the wire-entry holes in the box sides, the apertures in the lining being of less diameter than those in the side wall of the box, 60 for the purpose specified.

3. In a fuse box, a sheet metal box body, an insulating base plate secured on the bottom thereof, a series of fuse terminal clips mounted on said base, the sides of the 65 box being apertured to admit lead wires to said clips, said box sides having slots extending from their edges to the wire holes to permit the introduction of the lead wires into the latter for connection to the binding 70 screws.

4. In a fuse box, a sheet metal box body, an insulating base plate secured on the bottom thereof, a series of fuse terminal 75 clips mounted on said base, the sides of the box being apertured to admit lead wires to said clips, said box sides having slots extending from their edges to the wire holes to permit the introduction of the lead wires into the latter for connection to the binding 80 screws, in combination with a lining sheet of insulating material facing said box sides and cut in register with the apertures and slots in the box sides, the apertures and slots in the lining being of less diameter in order 85 to maintain the lead wires out of contact with the box sides.

In testimony whereof I have signed my name to this specification.

GEORGE B. THOMAS.
